UNITED STATES PATENT OFFICE.

LAWRENCE E. GORDON, OF MARION, VIRGINIA, ASSIGNOR TO VIRGINIA TABLE COMPANY, INCORPORATED, OF MARION, VIRGINIA, A CORPORATION OF VIRGINIA.

DESIGN FOR A CHAIR BACK OR SIMILAR ARTICLE.

Application filed June 8, 1928. Serial No. 27,039. Term of patent 3½ years.

To all whom it may concern:

Be it known that I, LAWRENCE E. GORDON, a citizen of the United States, residing at Marion, in the county of Smyth and State of Virginia, have invented a new, original, and ornamental Design for a Chair Back or Similar Article, of which the following is a specification, reference being had to the accompanying drawing, forming a part thereof.

The figure is a perspective view of a chair back or similar article showing my new design.

I claim:

The ornamental design for a chair back or similar article as shown.

In witness whereof, I hereunto subscribe my name, this 4 day of June, 1928.

L. E. GORDON.
